PHONE AND METHOD OF MAKING SAME

Donald E. Rutter, East Cleveland, Harry B. Shapiro, Cleveland, and Walter J. Brown, Cleveland Heights, Ohio; said Harry B. Shapiro now by judicial change of name Harry B. Shaper; assignors to The Brush Development Company, Cleveland, Ohio, a corporation of Ohio

Application July 16, 1941, Serial No. 402,608

13 Claims. (Cl. 179—107)

Our invention pertains to earphones and more particularly to the small type of phone which is adapted to fit in a person's outer ear.

An object of our invention is to provide a small phone which is adapted to fit into ears of many different sizes and shapes.

A further object of our invention is to provide an insert type earphone in which the shape of the earphone case helps to hold the device in the wearer's ear.

Another object of our invention is to provide an insert type piezoelectric earphone shaped to accommodate a relatively large crystal unit and in which the shape of the case cooperates with retaining means to hold the device in the wearer's ear.

Still another object of our invention is to provide a piezoelectric earphone which is easily and quickly assembled.

It is also an object of our invention to provide an encased earphone in which one portion of the case is adapted to yieldably conform to the contours of the wearer's ear to cooperate with the general shape of the earphone to hold the device in the wearer's ear.

A further object of our invention is to provide an earphone having a cord connected to the leads of an electro-mechanical transducer in a manner to cause a pull on the cord to tighten the connection between the cord and the leads of the transducer.

Another object of our invention is to provide an insert earphone adapted to withstand rapid changes in the surrounding air pressure.

It is another object of our invention to provide an insert type earphone subassembly primarily adapted to be placed in a mass production case which will fit many different ears but which may readily be placed in a special case moulded to fit an unusual ear.

Still another object of our invention is to provide an insert type earphone subassembly which is operable without an enclosing case.

A further object of our invention is to provide a new and improved method of assembling an earphone.

Another object of my invention is to provide a diaphragm of large area for an insert type earphone and to position the diaphragm drive pin to obtain the maximum volume of displacement for a given amount of movement of the drive pin.

Other objects and a fuller understanding of my invention may be had by referring to the following detailed description and claims, taken in con-

junction with the accompanying drawing in which:

Figure 1 is an enlarged cross sectional view illustrating a step in the process of assembling an earphone in which a cutting die is shaping a diaphragm.

Figure 2 is an enlarged cross section illustrating the use of the cutting die as a jig for positioning some of the parts of the earphone.

10 Figure 3 is an enlarged cross sectional view illustrating a further step in the process of assembling the earphone.

Figure 4 is an enlarged isometric view of an earphone subassembly with portions broken away to more clearly illustrate the parts.

15 Figure 5 is an enlarged isometric view of another earphone subassembly with portions broken away.

Figure 6 is an enlarged plan view of the portion of the earphone which is adapted to fit against the wearer's ear.

20 Figure 7 is a slightly enlarged view showing an earphone in position in the wearer's ear.

Figure 8 is a sectional view taken along line 8—8 of Figure 6, and

25 Figure 9 is an enlarged sectional view taken along line 9—9 of Figure 8.

In the construction and assembly of piezo-electric earphones which are adapted to be inserted in a person's outer ear it is very important that the parts be accurately positioned with respect to each other, and especially important that the diaphragm and the crystal unit be accurately positioned with respect to each other. To effect this accurate positioning of parts for an earphone which is adapted to be made by mass production methods we have devised a novel earphone subassembly and a method of constructing it.

With reference to the drawing Figure 1 is a 30 cross-sectional view of a forming die 10, a cutting die 11, and a formed diaphragm 12 for an earphone unit. The forming die 10 is the male section of a pair of forming dies between which a sheet of metal foil or other suitable material

35 is placed to be squeezed to form the earphone diaphragm 12. The female section of the forming die (not shown) is then removed and the cutting die 11 is brought down on the diaphragm 12 to shear off the outside waste material 13.

40 With the cutting die 11 in place a mounting frame 14 is positioned against the diaphragm 12. This step is illustrated in Figure 2. An adhesive may be applied to either the frame or the diaphragm to cause them to stick together. In connecting

45 the frame 14 to the diaphragm 12 the cutting

die 11 acts as a jig to very accurately position the frame with respect to the diaphragm. The frame preferably engages the cutting die substantially entirely around its circumference but it may engage the die only at a few spaced intervals.

The frame 14 is formed of a plastic or other suitable material and has three notches 15 in it for receiving three corners of a piezo-electric crystal unit 16. Connected to the fourth corner of the crystal unit is a drive pin 17 which is adapted to be connected to and actuate the diaphragm 12 as an alternating current potential is applied to the crystal unit. The frame 14 also has a quirk or shoulder 8 for positioning the diaphragm 12.

Figure 3 illustrates the positioning of the crystal unit 16 in the mounting frame 14 in a manner to cause the crystal unit to be accurately placed with respect to the diaphragm. Three corners of the crystal unit are placed in the three notches 15 in the mounting frame 14 and the drive pin 17 is placed through a hole 18 in the diaphragm 12 and into a hole 19 in the die section 10. The hole 19 in the die section is slightly larger than the drive pin 17 to enable the pin to be easily positioned therein, and has a substantial length for receiving the pin 17 to cause the pin 17 to be accurately positioned with respect to the die section 10 and consequently accurately positioned with respect to the diaphragm 12 and the mounting frame 14. With the pin 17 in the hole 19 the crystal unit may be rotated slightly about the pin as a center to position the corners of the crystal unit in the centers of the three notches 15 in the mounting frame 14. Adhesive material may be applied to the three corners of the crystal unit either before or after the unit is positioned in the frame to fasten them to the frame 14, and adhesive may be applied to the drive pin to secure it to the diaphragm 12. The cutting die 11 may then be removed from the forming die 10 and from around the frame 14, and the frame 14 with its associated diaphragm and crystal unit may be removed from the die section 10.

By following these steps in assembling an earphone, an operative subassembly consisting of the frame 14, the diaphragm 12, and the crystal unit 16 is constructed in a manner which assures accurate alignment of parts even though the work is done rapidly. By utilizing the cutting die 11 as a jig to position the frame with respect to the diaphragm, and utilizing the die section 10 as a jig to position the crystal unit drive pin 17 with respect to the diaphragm 12 and the frame 14, the closest manufacturing tolerances may be maintained thereby assuring a high quality earphone subassembly.

After the earphone subassembly consisting of frame 14, diaphragm 12, and crystal unit 16 has been removed from the forming die 10, a guard plate 25 is secured by an adhesive or other suitable means to the edge of the diaphragm 12 to protect the diaphragm from deformation and puncturing during subsequent assembly work and while the earphone is being worn.

The diaphragm 12 is on the order of $\frac{3}{10,000}$ of an inch thick and the crystal is on the order of $\frac{3}{1,000}$ of an inch thick. Accordingly the subassembly must be handled carefully but when it is provided with a guard plate 25, and when the top surface of the crystal unit 16 is below the edge of the mounting frame 14 (as illustrated in Figure 4) extreme care which slows down subsequent assembly work does not have to be exercised. The subassembly may be handled to position it

in an earphone case or it may be packed to ship it to manufacturers who prefer to use their own earphone cases. This is highly desirable as many units may be mounted in standard mass production earphone cases which will fit most person's ears, but other units may be mounted on earphone cases moulded to fit ears which require special cases in order to provide sufficient support to hold the earphone in the user's ear. Therefore, in order to provide an earphone for all persons who might desire one it is necessary to have an operative subassembly which can be mounted into a special case without requiring the services of a specialist to do so, and which may be mounted in standard types of mass production cases.

The crystal unit 16 is comprised of two connected Rochelle salt crystal slabs 20 and two leads 40 attached to the slabs 20 and adapted to connect the earphone into an electrical circuit which applies an alternating current to the crystals 20 to cause the crystals 20 to vibrate and actuate the diaphragm 12 according to the well-known piezo-electric manner. For more detailed description of the piezo-electric action reference may be made to Charles B. Sawyer's Reissue Patent Number 20,680, and for a more detailed description of a three cornered mounting reference may be made to A. L. W. Williams' Patent Number 2,105,011. The leads 40 are very thin and in order to connect them into the electrical circuit we provide the mounting frame 14 with a terminal bar 41 about which the leads may be wrapped to provide a firm base for terminal clips 31. The terminal clips 31 (only one is shown) are connected in the electrical circuit and slide over the terminal bar 41 with a lead 40 positioned between each clip 31 and the terminal bar 41. The mounting frame 14 is preferably formed of a plastic material and accordingly no insulator is needed in the terminal bar between the two clips 31. However, if the terminal bar were made of a conductive material an insulator to electrically separate the two leads 40 could be added. A ridge 42 or notches 43 can be added to the terminal to prevent the two terminal clips 31 from sliding into engagement with each other.

Figures 5 and 6 illustrate two halves of an earphone case which is adapted to fit in many ears of different size and shape to hold the earphone in place. Figure 5 shows an outside portion 26 of an earphone case, and Figure 6 shows an inside portion 27 of an earphone case. The outside portion 26 constitutes that part of the case which can be seen in the ear of a wearer as is illustrated in Figure 7, and the inside portion 27 constitutes the part of the case which lies against the wearer's ear to help hold the earphone in place.

The outside portion 26 of the case is assembled with a circular guard plate 28 which is adapted to protect one side of the crystal slabs 20, a pair of wires 29, 30, and a pair of terminal clips 31 (only one shown) one for each wire 29, 30. The wires 29, 30 are connected in the electrical circuit which supplies the earphone, and pass through a hole 32 in a raised portion 35 in the case 26, through a hole 33 between the guard plate 28 and a raised lug 34, and connect to the terminal clips 31.

The case portion 26 is "egg" shaped in plan with a first end portion 44 and a second end portion 45. The end portions 44 and 45 are shaped as arcs of circles, the arc of the first end 44 having a radius which is greater than the radius of the arc of the second end portion 45, and the

sides of the case may be substantially straight lines tangent to the two arcs, or slightly curved lines joining the two arcs. The guard plate 28 is circular and has a radius slightly less than the radius of the first end portion 44 of the case portion 26. Accordingly when the guard 28 is placed in the first end of the case it will stay in that position, and a pull on the twisted cord 29, 30 will cause the guard plate to wedge into a narrower part of the case 26 to prevent further movement. An adhesive 46 may be placed around the edge of the guard plate 28 where the plate engages the case portion 26 to prevent the guard plate 28 from moving after it has been placed in the case 26.

To connect the operative subassembly to the case portion 26, the guard plate 28 is positioned over the crystal 20 and the operative subassembly and the case portion pushed together. The edge of the case portion 26 fits outside of a step 51 constituting part of the edge of the mounting frame 14.

The inside case portion 27 (Figure 6) is adapted to engage the diaphragm guard 25, the outside edge of the diaphragm 12, and a step 47 on the edge of the mounting frame 14, and lie between the outside case portion 26 and the wearer's ear. Suitable adhesive means may be applied between the frame 14 and the outside case portion 26, and between the frame and the inside case portion 27 to hold them together and to prevent moisture from entering the earphone.

A feature of our invention is to transfer a pull on the earphone cord 29, 30 with respect to the earphone case to the case without damaging the operating parts. This is effected by mounting the guard plate 28 directly to a portion of the case and by providing the raised lug 34 which operates as a snubber post. Figure 8 best illustrates the operation of the lug 34 as a snubber post. The cord 29, 30 enters the earphone through the hole 32 in the raised portion 35 of the outside case portion 26, passes through the hole 33 between the lug 34 and the guard plate 28, bends back upon itself around the lug 34, and is connected to the terminal clip 31 in such a manner that a pull on the cord 29, 30 causes the terminal clip 31 to more closely engage the terminal bar 41, and hence to more closely engage the lead 40. Most of the force of the pull on the wire 29, 30 is taken by the guard plate 28 and transferred to the case 26 and the rest of the pull is taken by the terminal bar 41 and transferred to the case 27.

The inside case portion 27 is comprised of a body portion 48 shaped in plan substantially the same as the plan of the outside case portion 26, a horn-shaped lug or ear engaging portion 49 connected to the body portion, and a snout 50. The lug 49 is adapted to lie in the groove between the helix 55 and the antihelix 56 of the ear and engage the bottom and both sides of the groove. It may be composed of a soft plastic material in order that it will adjust itself to slightly different shaped ears and aid in holding the earphone in place. By forming the lug 49 of a soft formable plastic material it will engage the bottom and both sides of the groove without excessive spring pressure against either the helix or the antihelix which in time is apt to cause discomfort no matter how slight the pressure is. The body portion 48 is formed of a yieldable plastic material which is fairly thick around the edges where it engages the mounting frame 14. The snout 50 is adapted to project into the ear canal which joins the outer ear with the inner ear. The snout 50 is

formed of a soft yieldable plastic material and with a cross section which tapers from fairly thick at the location where it joins the body portion 48, to thin at the apex. The apex may be completely sealed as is illustrated in the cross sectional view 9 or it may have an opening 57 as is illustrated in Figure 6. By forming the snout 50 of a yieldable material with a cross section tapering to thin at the apex discomfort to the wearer's ear is reduced. When the earphone is placed in the wearer's ear the snout 50 yieldably assumes the direction of the ear canal with very little pressure on the walls thereof and substantially completely seals the ear canal against extraneous sound entering from the outside and against sound from the earphone leaking to the outside. The body portion 48 and the snout 50 of the case portion 27 are soft and yieldable. Accordingly a careless person handling the earphone might squeeze it too hard and damage the diaphragm 12 and the crystal 20 were it not for the diaphragm guard 25. Further, in an earphone having a sound snout with opening 57 in its end it is probable that the wearer will at some time try to clean the earphone with a match, toothpick, or pin. The diaphragm guard 25 is positioned to prevent damage from this source. The guard 25 may be made of sheet metal or plastic material with holes 24 through it as is illustrated in Figures 8 and 9.

By forming the engaging portion 49 and the snout 50 of formable soft plastic material which yieldably conforms to the shape of the wearer's ear, and by shaping the case larger at the top than at the bottom, an earphone has been produced which can be successfully connected in many ears although the ears vary to a certain extent in size and shape. The smaller end portion 45 of the case is adapted to lie in the concha of the ear with the tragus 58 and the antitragus 59 engaging the top portion of the outside case 26, and with the raised portion 35 extending slightly out from between the tragus 58 and the antitragus 59. The curve of the engaging portion 49 and the snout 50 cooperate with the general wedge shape of the earphone case to prevent the earphone from sliding downward in the ear even though a fairly hard pulling force is exerted on the cord 29, 30.

The diaphragm 12 has a shape in plan substantially the same as the plan shape of the body portion 48 of the inside case portion 27. The end 65 of the diaphragm 12 is an arc of a circle and the end 66 of the diaphragm is an arc of a circle having a smaller radius than the radius of the end 65 and having a different center. Each of the two sides of the diaphragm 12 is a straight or slightly curved line joining the two arcs. This shape provides a diaphragm of maximum area for the earphone, but introduces a compliance along the major axis which reduces the efficiency of the piston action of the diaphragm. The major axis may be defined as the centerline of the diaphragm extending through the centers of the arcs which describe the ends of the diaphragm, or the major axis may be defined as the axis about which the diaphragm is symmetrical. To increase the efficiency of the piston action we have provided a diaphragm which is substantially conical in cross section and which is driven by the crystal unit 16 from off-center. The distance from the large end 65 to the apex of the diaphragm being greater than the distance from the small end 66 to the apex. This combination of an off-center drive for a conical diaphragm which is "egg-shape" in plan provides substantially the maximum air

displacement for a given movement of the crystal drive unit 18. By connecting the drive pin off-center the shorter side of the diaphragm becomes more stiff than the longer side and tends to act as a lever to increase the movement of the longer side of the diaphragm thereby increasing the total volume displaced by the entire diaphragm. Further, it provides space for a larger crystal unit 20 thereby increasing the amount of movement at the apex of the diaphragm.

If it is desired that the earphone be used in airplanes where the pressure around the earphone is subject to rapid changes we provide a pressure equalizing hole 23 in the outside case portion 26. The hole 23 communicates with the inside of the earphone on the convex side of the diaphragm to establish an air passage for equalizing the internal air pressure with the external air pressure. A small amount of air leakage between the snout 58 and the walls of the ear canal will enter the inside of the earphone on the concave side of the diaphragm through the opening 57 in the snout thereby equalizing the air pressure on both sides of the earphone diaphragm 12. The air pressure on both sides of the diaphragm of the wearer's ear will also be substantially equalized due to a slight amount of leakage around the snout 58.

Although we have described our invention with a certain degree of particularity it is to be understood that various changes can be made in the size, shape, and arrangement of parts without departing from the spirit and scope of our invention.

We claim:

1. The process of constructing an operative earphone subassembly having a preformed frame and a crystal unit; the steps of said process comprising: forming a diaphragm from sheet material using die means, cutting said diaphragm from said sheet material using die means, fastening said frame means to said diaphragm means using said cutting die means to accurately position the frame means with respect to the diaphragm means, and fastening said crystal unit to the frame means and to the diaphragm means using said forming die means to accurately position the said crystal unit with respect to the said diaphragm.

2. The process of assembling an earphone having a crystal unit with a drive pin which comprises the steps of cutting a diaphragm between a first and a second die section, securing a preformed frame member to said diaphragm utilizing said second die section as a jig to accurately position the said frame with respect to the said diaphragm, securing said crystal unit to the said frame utilizing said first die section as a jig to accurately position the said crystal unit with respect to the said diaphragm, and securing the drive pin of the said crystal unit to the said diaphragm.

3. The process of constructing an earphone subassembly comprised of a diaphragm, a frame, and a crystal unit; the steps of said process comprising: cutting said diaphragm between die means, securing said frame to said diaphragm utilizing said die means to accurately position the frame with respect to the diaphragm, and securing said crystal unit to said frame utilizing said die means to accurately position the crystal unit with respect to the diaphragm.

4. The process of constructing an operative earphone subassembly having a preformed diaphragm, a preformed frame, and a preformed

crystal unit; the steps of said process comprising: die cutting said formed diaphragm, securing said frame to said diaphragm utilizing said cutting die to accurately position the frame with respect to the said diaphragm, and securing said crystal unit to said frame and to said diaphragm utilizing said die to accurately position the crystal unit with respect to the said diaphragm.

5. In an insert earphone; a case adapted to be mounted within the ear of a wearer, a non-conductive terminal bar within and supported by said case, an electromechanical transducer unit including lead means supported in said case with the said lead means engaging the terminal bar, cable means extending into said case, terminal clip means connected to said cable means and adapted to slidably engage said lead means and said terminal bar, and means for causing said terminal clip means to slide into closer engagement with the said terminal bar as said cable means is pulled from outside of the said case.

6. In a piezoelectric insert earphone, a case adapted to be mounted within the ear of a wearer, a terminal bar positioned within and supported by said case, a piezoelectric unit including lead means positioned in said case and said lead means engaging said terminal bar, cable means extending into said case, terminal contact clip means connected to said cable means and adapted to slidably engage said terminal bar and said lead means, and snubber means engaging said cable means between the terminal contact clip means and the point where the said cable means extends through the said case into the said enclosure.

7. A cable connection for an encased piezoelectric unit having a Rochelle salt crystal unit with lead means connected thereto comprising, in combination, a terminal bar in engagement with said lead means, terminal contact clip means adapted to slidably engage the said terminal bar to establish an electrical connection with said lead means, cable means connected to said terminal contact clip and adapted when subject to a pull to cause said contact clip to more firmly engage said terminal bar.

8. An insert type of earphone, comprising in combination, a piezoelectric crystal unit having leads adapted to connect said unit in an electrical transmission path; a conical diaphragm having an off-center apex, a drive pin connected to said crystal unit and connected to said off-center apex of said diaphragm; a case enclosing said crystal unit, said diaphragm, and said drive pin; said case including a soft flexible portion adapted to fit against the ear of the wearer; and guard means positioned between the soft portion of the case and the diaphragm to protect the diaphragm.

9. In an earphone, a mounting member having a body portion conforming substantially to the meatus of the ear, an engaging portion integral with said body portion and adapted to lie in the groove in the wearer's ear between the helix and the antihelix, and a hollow tapering sound snout having a first end portion integral with said body portion and a second end portion adapted to engage the sides of the ear canal, said snout having a cross-sectional thickness progressively decreasing from said first end portion to said second end portion, and a telephone receiver connected to said body portion.

10. In an earphone, a case which is rounded at a first large end portion and rounded at a second smaller end portion and which has side portions joining the first larger end portion with the

second smaller end portion to form a generally tapering case, a disk of a size slightly smaller than the larger end portion of said case portion slidably mounted in the larger end portion thereof, a transducer mounted within said case and including lead means extending through said case to the outside thereof, said lead means being anchored to said disk whereby a pull on said lead means from outside of said case causes said disk to slide toward the smaller end portion of said case and wedge between the said side portions thereof.

11. In an insert type of earphone; electromechanical transducer means for connection in an electrical transmission path, diaphragm means including a drive pin connected to said transducer means, a case enclosing said transducer means and said diaphragm means and including a soft flexible portion adapted to fit against the ear of the wearer, and guard means connected to said case and positioned between the soft portion of the case and the diaphragm to protect the said diaphragm.

12. The invention as set forth in claim 11 further characterized in this, that said guard means extends substantially entirely across one face of said case and has a plurality of small holes therethrough for permitting transmission of sound pressure from said diaphragm into the soft flexible portion which fits into a wearer's ear.

13. In an earphone, a case which is rounded at a first end portion and rounded at a second smaller end portion and which has side portions joining the first end portion with the smaller end portion to form a generally tapering case adapted to be mounted within the ear of a wearer, a disk of a size slightly smaller than the first end portion and larger than said smaller end portion slidably mounted in the larger end portion thereof and having a snubber post mounted on one face thereof, an electrically non-conductive terminal bar within and supported by said case, an electro-mechanical transducer unit including lead means supported in said case with the said lead means 15 engaging the terminal bar, cable means extending into said case around said snubber means and having terminal clip means connected on the end thereof and adapted to slidably engage said lead means and said terminal bar whereby upon said 20 cable means being pulled away from said case said disk tends to slide toward the smaller end portion of said case and wedges between the side portions thereof and said terminal clip means slide into closer engagement with said terminal bar, thereby relieving the transducer lead means of all tensional strain.
